(57) **CLAIM**

The ornamental design for a cabinet, as shown and described.

DESCRIPTION

FIG. 1 is a front, left, upper perspective view of a first embodiment of a cabinet embodying my new design;

FIG. 2 is a front elevational view thereof;

FIG. 3 is a left side elevational view thereof, the right side elevational view being a mirror image thereof;

FIG. 4 is a top plan view thereof;

FIG. 5 is a rear elevational view thereof;

FIG. 6 is a front, left, upper perspective view of a second embodiment of a cabinet embodying my new design;

FIG. 7 is a front elevational view thereof; and,

FIG. 8 is a left side elevational view thereof, the right side elevational view being a mirror image thereof.

The broken line representations of top cabinet structure in FIGS. 1, 4, and 6, of rear cabinet structure in FIG. 5, of drawers in FIGS. 1-3, of doors in FIGS. 6-8, of drawer pulls in FIGS. 1-2, and of door pulls in FIGS. 6-7, are for environmental purposes only and form no part of the claimed design.

The broken away portions shown in FIGS. 1-2, and 4-7 represents that no particular width is claimed.
